UNITED STATES PATENT OFFICE.

ALGERNON WILLIAM DARGUE AND FREDERICK LEWIN DARGUE, OF HALIFAX,
ENGLAND.

DRAWING APPARATUS.

Application filed January 29, 1923. Serial No. 615,681.

To all whom it may concern:

Be it known that we, ALGERNON WILLIAM DARGUE and FREDERICK LEWIN DARGUE, subjects of King George V, of Great Britain, residing at Halifax, in the county of York, England, have invented a new and useful Improvement in or Relating to Drawing Apparatus (for which I have filed an application in Great Britain, on November 18, 1921, Patent No. 188214), of which the following is a specification.

Our invention in or relating to drawing apparatus has reference to what are known as universal drawing or drafting machines and has for its object to improve upon the present constructions.

According to, and for the purposes of, our invention we employ a drawing board, a straight-edge for use therewith, and means to maintain the straight-edge in true horizontal position as it is moved over the surface of the board.

The board may be supported on a suitable stand provided with mechanism whereby the vertical height of the board, and its angular position, can be adjusted.

The straight-edge carries a bar, the upper edge of which is parallel to the working edge of the straight-edge, and movable along this bar is a plate, on which is pivotally mounted a member having two arms extending at right angles and adapted to carry straight-edges or scales.

Means are provided to enable the two-armed member or lever to be locked in any angular position desired, and means are also provided whereby the plate carrying the said member or lever can be automatically and regularly spaced along the bar on which it is movable.

If the board is mounted on a stand as above set forth, means in the form of cords and weights are provided to counter-balance the weight of the straight-edge and of the parts carried thereby, when the board occupies a vertical or angular position.

The invention will be more fully described with the aid of the accompanying drawing in which

Fig. 1 is a plan or front view of a drafting machine constructed according to the invention, the automatic spacing means being omitted;

Fig. 2 is a detail section showing the method of attaching to the board the toothed

guiding racks for the straight-edge, shown in Fig. 1, said Figure 2 also showing an arrangement whereby the straight-edge can be removed when desired.

Fig. 3 is a section on an enlarged scale, 60 on the line A, A, Fig. 1.

Figs. 4 and 5 are, respectively, an elevation and a plan view of a suitable means for effecting automatic spacing of the drawing arms or scales across the board; and

Fig. 6 is another elevation of the spacing means, showing the parts in different positions from those shown in Fig. 4 and being furnished to facilitate the description of the action of such spacing means.

Referring to the drawings 1 represents a drawing board, and 2, 2 toothed racks applied to its side edges. These racks are preferably attached to metal plates 3, see Fig. 2, which are screwed to the edges of the board. The edges of the plates are preferably arranged to shroud or project slightly above the tooth level of the racks and thus prevent the teeth of the pinions hereinafter referred to from coming into contact with the woodwork of the board.

A straight-edge 4, for use with the board, has a hand rail 5, through which passes a spindle 6 having on its ends pinions 7, 7, adapted to mesh with the racks 2, 2. The teeth of the racks and pinions are preferably skewed or cut at an angle as shown.

The upper side of the board, at each end thereof is provided with a guide pulley 8, and if the board is mounted upon a stand to permit its angular position to be adjusted, cords 9, 9, attached to the straight-edge and passing over the pulleys 8, 8, are suitably weighted to counter-balance the weight of the straight-edge and of the parts, hereafter to be described, carried thereby.

The ends of the straight-edge are provided with pivoted members or brackets 10, 10, carrying rollers 11, 11 which are adapted to engage in grooves 12, 12 in the undersides of the racks and hold the straight-edge in contact with the surface of the board. The members 10, 10 are slotted as at 10' to permit the rollers 11 to drop out of the grooves when the clamping bolts 13 are slackened. The members 10 can then be moved about their pivots to carry the rollers outwards clear of the racks and the straight-edge can then be removed from the board.

Secured at its ends to the surface of the

straight edge and spaced at a suitable distance therefrom is a bar 14, preferably of metal, the upper and lower edges of which are truly parallel to the working edge 4' of the straight-edge. The edge 4' is the upper edge when the drawing board is mounted in a vertical or inclined position.

Slidable between this bar or runway 14 and the surface of the straight-edge is a plate 15 provided with rollers 16, 16 which are adapted to run on the upper edge of the bar.

The plate 15 extends a suitable distance below the lower edge of the bar 14 and carries a spring member 17 the ends of which bear, by suitable rollers 17', 17', against the lower edge of the bar and hold the rollers 16, 16, in contact with the upper edge of the bar.

A suitably shaped bracket 18, secured to the plate 15 by a bolt 19, carries a roller 20 of suitable material such as rubber which bears upon the front surface of the bar 14 and is adapted to take the weight of the plate off the surface of the straight-edge. The plate 15 can, by the above means, be moved easily and truly along the bar 14 from end to end thereof, and the roller 20 bears on the bar with sufficient force to guard against accidental displacement of the plate along the bar.

A centrally disposed bracket 21 serves to stay the centre of the bar or runway 14 and is suitably hollowed out, as shown, on its underside to permit of the projecting part 35 of the plate 15 with its spring member 17 and rollers 17', 17', to pass beneath same.

The plate 15 projects a suitable distance above the bar 14 and has its upper edge made semi-circular in shape as shown.

Pivoted on the centre from which the semi-circular edge of plate 15 is struck, is a member having two arms 22, 22', extending at a right angle to each other. These arms are adapted to receive straight-edges or scales 23, 23' and they are of such a length as to extend to about midway of the length of the scales employed, so that by providing attachments, such as screws, 24, 24' at the extreme ends of the arms, and other attachments 25, 25' near the inner ends of the scales the latter are held rigidly without any play.

The arm 22 carries a spring plunger 26 adapted to engage, when the arm is appropriately positioned, in one of a series of holes 27 on the plate 15, so as to hold the arms in a definite angular position with respect to the straight-edge, say with the arm 22 vertical or at thirty, forty five or sixty degrees or horizontal.

The arm 22' carries a vernier 28 adapted to work in conjunction with a suitably divided arc 29 on the plate 15. A clamping bolt 30 is provided to enable this arm 22' to be set in any position of fine angular adjust-

ment that may be required, the spring plunger 26 of the other arm being of course held clear of the holes 27 to permit this adjustment to be made. A finger lever 26' is provided to enable the plunger 26 to be so raised. A central knob 31 secured to the two armed lever or member enables the latter to be turned to adjust the set square formed by the straight-edges or scales 23, 23' and to facilitate movement of the apparatus over the surface of the board.

To enable the plate 15 and the parts carried thereby to be automatically spaced along the runway 14, the bracket 18 may carry a pivoted member 32 having pivotally attached thereto a pawl 33. A spring 34 connected to the member 32 and to the pawl acts to draw the latter inwardly. The end of the pawl is formed as a tooth to engage serrations on the surface of the bar 14 which serrations may conveniently be divisions of a measure of length as indicated in Figs. 1 and 5.

An extension 32' of the member 32, beyond its pivot centre, carries an adjusting screw 35 adapted to contact with the surface of the plate 15.

Fig. 4 shews the normal position of the spacing apparatus. If the end of the member 32 be depressed, by finger pressure on the button 36, the end of the pawl engages in one of the serrations of bar 14 and forces the plate 15 and parts carried thereby to the right, as illustrated by Fig. 6. On release of member 32, the spring 34 pulls on the pawl 100 and causes member 32 to swing upwardly, until the end of screw 35 abuts on to plate 15, thereby limiting the inward movement of the pawl and positioning it for the next operation.

By constructing drawing apparatus as above set forth, we obtain a universal drafting machine without any projections beyond the edges of the board other than the usual overlapping of the set square when the latter is employed in either extreme horizontal position. A full length horizontal line can be drawn at any time and parallel angular lines starting from points in the same horizontal plane can be drawn. The scales, if employed, are available across the whole width of the board in any position, either horizontal or angular, and they can be readily locked in any desired position.

The details of construction of the parts constituting the improved apparatus may vary.

Having thus described our invention, what we claim as new and desire to secure by Letters Patent is:—

The combination, with a straight-edged member provided with serrations, and a plate slidably mounted on the said member, of a spacing device comprising a depressible spacing arm supported pivotally by the said

plate, a pawl pivoted to the spacing arm and engaging with the said serrations, an extension arm secured to the spacing arm and projecting on the other side of its pivot 5 from the pawl, a stop screw engaging with the free end portion of the extension arm and bearing on the said plate when the spacing arm and its pawl are raised with respect

to the said member, and a spring secured between the said spacing arm and pawl and 10 operating to raise them.

In testimony whereof we affix our signatures.

ALGERNON WILLIAM DARGUE.
FREDERICK LEWIN DARGUE.
